DESIGN FOR A SHOE

Carl Stix, Cincinnati, Ohio, assignor to Plaut-
Butler Inc., Cincinnati, Ohio, a corporation of
Ohio

Application November 15, 1934, Serial No. 54,031

Term of patent 3½ years

To all whom it may concern:

Be it known that I, Carl Stix, a citizen of the United States, residing at Cincinnati, in the county of Hamilton and State of Ohio, have invented a new, original, and ornamental Design for a Shoe, of which the following is a specification, reference being had to the accompanying drawing, forming a part thereof.

The figure is a side elevation of a shoe showing my new design, the greater portion of the shoe being shown in dot and dash lines, and the opposite side presenting substantially the same ap-

pearance as the one shown. The dominant features of my design reside in the stitching and perforations as shown in the full lines, the stitching or bounding forming a border for the perforations, a lacing of a color or shade contrasting from that of the vamp, threaded through a row of perforations and a background of contrasting shade or color behind the open perforations.

I claim:

The ornamental design for a shoe substantially as shown and described.

CARL STIX.
